(57) **CLAIM**

I claim the ornamental design for a reclining chaise frame, as shown and described.

DESCRIPTION

FIG. 1 is a top left perspective view of a reclining chaise frame in an extended position, showing my new design;

FIG. 2 is a front elevation view thereof;

FIG. 3 is a right side elevation view thereof, the left side elevation view being a mirror image thereof;

FIG. 4 is a bottom plan view thereof;

FIG. 5 is a rear elevation view thereof;

FIG. 6 is a cross-sectional view of the inside-side of the reclining chaise frame taken in the direction of section 6-6 of FIG. 4;

FIG. 7 is a top left perspective view of a reclining chaise frame in a collapsed position, showing my new design;

FIG. 8 is a front elevation view thereof;

FIG. 9 is a right side elevation view thereof, the left side elevation view being a mirror image thereof;

FIG. 10 is a bottom plan view thereof;

FIG. 11 is a rear elevation view thereof;

FIG. 12 is a cross-sectional view of the inside-side of the reclining chaise frame taken in the direction of section 12-12 of FIG. 10; and,

FIG. 13 is a top left perspective view of a reclining chaise frame in extended position shown in an environment of use. Broken lines in the drawings represent unclaimed environmental subject matter and form no part of the claimed design.
